UNITED STATES PATENT OFFICE

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE

FEELER MECHANISM FOR LOOMS

Application filed May 14, 1929. Serial No. 362,920.

This invention relates to feeler mechanisms for looms and more particularly to feeler mechanisms of the side slipping type, whereby the operative condition of the loom is changed from time to time.

Much thought and inventive ingenuity have been exercised in attempts to secure a feeler mechanism sufficiently sensitive both to the presence and absence or substantial absence of filling in the shuttle to prevent excessive waste on the one hand and imperfect cloth on the other.

In feeler mechanisms of the side slipping type where the feeler is subjected to the action of spring means for moving it to feeling position, there are two main factors which contribute largely in the sensitiveness of the feeler operation. When a working supply of filling is present in the shuttle on a detecting beat, the filling engaging end of the feeler, usually provided with teeth or other filling engaging means, should be yieldingly held to insure that the filling engaging end of the feeler shall sink into the filling to prevent side slipping movement of the feeler as the lay moves frontwardly. Owing to the different kinds of filling that may be used in connection with the same feeler mechanism, or the different speeds at which the loom may be run, variation becomes necessary in the means for holding the feeler in its feeling position to insure that the end of the feeler may sink into and be held from side slipping movement by a working supply of filling.

The feeling position of the feeler itself likewise becomes an important factor in sensitizing the feeler both to the presence and substantial absence of filling.

One of the objects of the present invention is to provide a feeler mechanism of the side slipping type with means for insuring the proper position of the feeler when in feeling position and spring tension varying means that may enable the feeler to be held with varying spring tension in feeler position suitable to the particular kind of filling in use or the speed of the loom.

In certain respects the feeler mechanism of the present invention is a further development of that shown and described in the

Harry A. Davis Patent, No. 1,670,283, May 15, 1928, and as exemplified in the Davis patent, the set of the feeler when in feeling position should be accomplished while the loom and feeler continue in operation, so that during the adjustment of the feeler and the spring connected thereto the action of the feeler may be observed and changed while the loom continues to run.

The invention and novel features thereof will best be made clear from the following description and the accompanying drawings of one good form thereof.

In the drawings:

Fig. 1 is a plan view of a feeler mechanism containing the present invention;

Fig. 2 is a section on the line 2—2 of Fig. 1;

Fig. 3 is a section on the line 3—3 of Fig. 1;

Fig. 4 is a section on the line 4—4 of Fig. 1; and

Fig. 5 is a detached plan view of a pin and eccentric for determining the lateral feeling position of the feeler.

The feeler mechanism of the present invention is primarily intended to be associated with filling replenishing mechanism, in order to call for a change of filling when that in the shuttle has become substantially exhausted, but since the details of the replenishing mechanism are not essential to the feeler operation and are now well understood in the art, an illustration and description thereof is unnecessary.

In the drawings the feeler stand comprises a base member 1 and a cover member 2 which may be secured in fixed position on the loom frame by any appropriate usual means, such, for instance, as more fully described in the Davis patent.

Between the base and cover portions of the feeler stand the feeler member 3 is mounted for movement towards and from the front of the loom and also in a direction longitudinally of the shuttle. As shown, the feeler member 3 has its rear end portion provided with a roughened surface which, in the present instance, is in the form of a spring or coil of wire 4, the coils of which are adapted to sink into a working supply of filling on a

detecting beat and prevent side slipping movement of the feeler.

Extending through an opening 5 in the feeler stand is a transmitter 6 between the 5 train of mechanism for effecting replenishment of filling and the feeler member 3, the construction being such that should the feeler side slip on a detecting beat, the transmitter 6 will be moved longitudinally to initiate 10 replenishment of filling.

The feeler member 3 has a laterally extending arm 7, the end portion 8 of which is adapted to rest against a stop bearing 9 on the feeler stand when the feeler is in its rear- 15 ward feeling position.

The feeler member 3 is normally under the control of a spring tending to hold the feeler in its rearward feeling position, and, as shown, the described spring, as indicated at 20 10, has one end thereof secured to the laterally extending arm 7 at 11, while the other end of the spring at 12 is connected to a spring tensioning member mounted on the feeler stand, the purpose of which is to vary 25 the spring tension in accordance with the character of filling in use or the speed of the loom, to insure that the filling engaging end of the feeler will properly cooperate with the filling in the shuttle and be held from side 30 slipping movement thereby.

As more clearly indicated in Fig. 4, the spring tensioning member comprises a slide 13 extending through a bearing 14 at the front of the feeler stand, and at its rear portion 35 the slide 13 has a lug or projection 15 to which the rear end of the spring 10 is connected. The spring tensioning member or slide 13 has its frontwardly extending stem 16 threaded, and means are provided for moving 40 the slide rearwardly or frontwardly, as the case may be, to vary the tension of the spring in accordance with the conditions of the filling and loom speed.

As shown, the feeler stand has an arm 17 45 at its front portion through which the stem 16 of the feeler member extends. The arm 17 is bifurcated, as shown, to provide an opening 18 to receive a thumb nut 19 threaded to the feeler stem, the construction being 50 such that upon rotation of the thumb nut 19 the tensioning member or slide 13 may be moved towards or from the rear of the loom thereby varying the tension of the spring 10 while the loom and feeler continue in operation.

The thumb nut 19 being located at a fixed point and threaded to the stem of the tensioning member, may be manipulated to change the tension of the spring 10, while 55 both the loom and feeler remain in action, with the result that the loom attendant may observe the action of the feeler upon the filling in the shuttle and be guided thereby in the adjustment of the spring tension.

Different kinds of filling will require dif-

ferent tensioning effect of the spring 10 upon the feeler to insure that the filling engaging end of the feeler may engage the filling with holding effect, and the same characteristic action may be present where, with the same 70 filling in the shuttle, the speed of the loom itself is changed.

When the loom attendant has adjusted the spring 10 by or through the tensioning member or slide 13 and has observed that the 75 spring tension is suitable both to the filling in use and the speed of the loom, he may secure the spring tensioning member in its adjusted position by a set nut 20 threaded to the stem 16 of the tensioning member. Thus, 80 while the loom and feeler mechanism continue to operate, the tension of the spring may be varied to suit the kind or character of filling in the shuttle and the speed of the loom, to insure that the filling engaging end of 85 the feeler shall contact with the filling with holding effect to prevent side slipping movement of the feeler when a working supply of filling is present in the shuttle on a detecting beat.

As will be observed from Fig. 4, the lug or projection 15 extending upwardly from the spring tensioning member rides along the under surface of the cover 2 of the feeler stand, thereby obviating all liability of the 90 rear end of the spring becoming detached. In the construction shown, the end of the projection or pin 15 rides in a groove or guide-way 21 formed in the under surface of the 95 cover plate 2.

The other factor which contributes to the 100 sensitiveness of the feeler to either the presence or substantial absence of filling is dependent upon the lateral position of the feeler when it is in its rearward feeling position, and such lateral position which, in accordance 105 with the present invention, may be varied, should be observable and noted during the operation of the loom and feeler mechanism, so that proper adjustment of the feeler to its 110 feeling position may be made based upon the loom attendant's observation of the feeler action.

In the present instance of the invention, a pin 22 extends through the cover plate 2 115 of the feeler stand and has a bearing in the base portion 1, as indicated in Fig. 3, and an eccentric 23 is connected to the pin 22 and constitutes a variable stop for the lateral position of the feeler member 3. The upper 120 end of the pin 22 is provided with a groove 24 to receive an instrument for turning it to properly position the eccentric and feeler member when the set nut 25 is released.

Since the feeler member 3 rests against the surface of the eccentric during its movement towards and from the front of the loom, it is evident that the position of the eccentric 125 will determine the path of movement of the feeler member.

From the construction described as one good form of the present invention, it will be noted that the tension of the spring 10 and the lateral position of the feeler may both be varied while the loom and feeler mechanism continue in operation, so that the loom attendant may observe the conditions and make proper changes to meet the desired ends.

In the present instance of the invention, the cover plate 2 is provided with an opening 26 through which the position of the feeler and the transmitter 6 may be observed, although this may not always be necessary.

The feeler stand may be secured to its support by a bolt 27, and the cover plate and base of the feeler stand may be held together by a screw or other means 28. In Fig. 1, the shuttle 29 is shown as of the usual filling changing type and is provided with the bobbin holding jaws 30 for detachably holding the bobbin or filling carrier on which the filling 31 is wound, and, as usual in this type of shuttle, the front wall thereof is provided with an opening 32 which registers with a corresponding opening in the front wall of the shuttle box, as usual, to permit the entrance of the feeler member to feel for the filling.

When a working supply of filling is in the shuttle, as indicated in Fig. 1, the filling engaging end of the feeler under the adjusting tension of the spring 10 will engage the filling with holding effect and prevent side slipping movement of the feeler, but when the filling is substantially exhausted, the feeler will side slip and call for a change of filling.

What is claimed is:

1. In a feeler mechanism for looms, the combination of a feeler stand, a side slipping feeler mounted for movement towards and from the front of the loom, a spring normally acting upon the feeler to hold it in rearward feeling position, a spring tensioning slide mounted for movement towards and from the front of the loom and connected to the spring, and means for moving the slide towards and from the front of the loom for varying the resistance of the spring to frontward movement of the feeler by the filling while the loom continues to run and the feeler continues in action that the feeler action upon the filling may be observed and changed during the loom and feeler operations.

2. In a feeler mechanism for looms, the combination of a feeler stand, a side slipping feeler mounted for movement towards and from the front of the loom, a pull spring normally acting upon the feeler to hold it in rearward feeling position, a spring tensioning slide mounted upon the feeler stand for manual movement towards and from the front of the loom and having the rear end of the spring connected thereto, and means for varying the position of the tensioning member towards and from the front of the loom and the consequent resistance of the spring

to feeler movement while the loom and feeler continue to operate that the feeler action upon the filling may be observed and changed while the loom continues to run.

3. In a feeler mechanism for looms, the combination of a feeler stand, a side slipping feeler having a laterally extending arm, a stop on the feeler stand engaged by said arm when the feeler is in rearward feeling position, a spring having one end connected to the feeler, a spring tensioning slide connected to the feeler stand and having a lug to which the other end of the spring is connected, and means accessible and operable to move the slide and vary the spring stress upon the feeler while the loom and feeler continue in operation.

4. In a feeler mechanism for looms, the combination of a feeler stand, a side slipping feeler having a laterally extending arm, a stop on the feeler stand engaged by said arm when the feeler is in rearward feeling position, a spring having one end connected to the feeler, a spring tensioning slide connected to the feeler stand and having a lug to which the other end of the spring is connected, and means at the front of the feeler stand accessible and operable to move the slide and vary the spring stress upon the feeler while the loom and feeler continue in operation.

5. In a feeler mechanism for looms, the combination of a feeler stand, a side slipping feeler mounted for movement towards and from the front of the loom, a spring having its front end connected to the feeler, a spring tensioning slide mounted for manual movement towards and from the front of the loom and connected to the rear end of the spring, and means manually operable during the loom operation to move the slide and thus vary the action of the spring that the feeler action upon the filling may be observed and changed while the loom and feeler continue in operation.

6. In a feeler mechanism for looms, the combination of a feeler stand, a side slipping feeler mounted for movement towards and from the front of the loom, a spring having its front end connected to the feeler, a spring tensioning slide mounted for manual movement towards and from the front of the loom, a lug at the rear part of the slide to which the rear end of the spring is connected, and means manually movable during the loom operation to change the position of the tensioning slide and consequently the action of the spring upon the feeler while the loom and feeler continue in operation.

In testimony whereof, I have signed my name to this specification.

HARRY A. DAVIS.
